UNITED STATES PATENT OFFICE.

CHARLES E. KOSTER, OF CHICAGO, ILLINOIS.

DOLEY FOR SEPARATING FORDSON TRACTORS.

Application filed October 15, 1920. Serial No. 417,073.

To all whom it may concern:

Be it known that I, CHARLES E. KOSTER, a citizen of the United States, residing at Chicago, in the county of Cook and State of Illinois, have invented certain new and useful Improvements in a Doley for Separating Fordson Tractors; and I do hereby declare the following to be a full, clear, and exact description of the invention, such as will enable others skilled in the art to which it appertains to make and use the same.

This invention has relation to certain new and useful improvements in a doley or a jack for separating Fordson tractors and has for its primary object the provision of a raising and supporting device for the sections of the tractor so as to permit of separation of the sections while resting on the doley or jack.

The invention has for another object the provision of a doley or jack for separating Fordson tractors and which will be especially adapted for use in connection with the Fordson type of tractor, one of the raising and supporting members of the device being securely mounted upon the track rails while the other raising and supporting member of the device is movable longitudinally upon said track rails, whereby this second member may be properly positioned beneath the forward section of the tractor.

The invention has for a further object the provision of a doley or separator for tractors in which the rear axle and transmission housing supporting member may be stationary while the member for raising and supporting the motor part of the tractor may be moved to any position desired upon the track rails.

The invention has for a still further object the provision of a doley or jack of the character stated which will be of comparatively simple construction and operation and which will be highly efficient in use so that the front and rear portions of the tractor may be readily raised and separated and supported when in separated condition or when removing or replacing the wheels upon the axles of the tractor.

The invention has for still another object the provision of a doley or jack of the character stated in which the forward jack structure may be readily adjusted upon the track

with respect to the stationary or immovable jack structure and each jack structure adjusted vertically independently of the other for raising separately the sections of the tractor.

With the foregoing and other objects in view, as will appear as the description proceeds, the invention consists in the novel construction, combination and arrangement of cooperating elements as hereinafter more specifically set forth, claimed and shown in the accompanying drawings forming a part of the present application and in which:

Figure 1 is an elevation of the complete device in use.

Figure 2 is a transverse section on the plane of line 2—2 of Figure 1.

Figure 3 is a transverse section on the plane of line 3—3 of Figure 1.

Figure 4 is a transverse section on the plane of line 4—4 of Figure 1.

Referring more in detail to the drawings in which similar reference characters designate corresponding parts throughout the several views, 1 indicates the rails of the track which are connected by suitable transverse connecting members 2 at the forward end of the track.

The lower or base member 3 of the rear stationary or immovable track structure is secured to the rails 1 by suitable securing bolts 4 or the like passed through the lower portion of the depending supporting legs 5 formed at the corners of the base member 3. This base member 3 has an enlarged or thickened central portion provided with an internally threaded opening forming a central socket 6 for the adjusting screw 7 to extend through, the screw 7 having its upper end secured within a seat 8 formed centrally in the lower face of the upper supporting plate 9 for the rear axle and transmission housing section of the tractor, as indicated at 10 in the drawings. See Figure 1. A hand wheel 11 is mounted on the screw 7 for raising and lowering the supporting plate 9. This plate 9 is provided at its front and rear edges with supports 12 one of which has a concave upper face 13 as will be readily understood by

referring to the drawings, so that the rear axle and transmission housing section of the tractor may be properly supported upon the

plate 9. The corner guide posts 14 are carried by the supporting plate 9 depending from the corners of the latter, said corner posts 14 extending through suitable guide openings 15 formed vertically in the base plate 3.

In order to raise and support the forward portion 16 of the tractor, I have provided a movable jack structure which includes a base plate 17 having depending side bracket members 18 at the corners thereof and through which the shafts 19 are extended to support the wheels 20 adapted to ride on the rails 1 so that the forward jack structure may be adjusted upon the track with respect to the stationary or immovable jack structure for the rear axle and transmission housing section of the tractor, as previously described.

The base plate 17 of the forward jack structure has a central socket 21 formed therein and through which the adjusting screw 22 extends, said adjusting screw being carried by and depending from the central portion of the upper or supporting plate 23, as shown in the drawings. The hand wheel 24 is threaded upon the adjusting screw 22 for the purpose of raising and lowering the supporting plate 23. The supporting plate 23 is provided with transverse supporting flanges 25 extended upwardly from its upper face and at the ends thereof, one of said flanges 25 having a concaved upper face 26 to conform to the body or base of the motor section of the tractor, as shown in Figure 3 of the drawings. The guide posts 27 are also provided for the forward jack structure and depend from the corners of the supporting plate 23 thereof, said guide posts 27 projecting through sockets or guide openings 28 formed in the corner portions of the base plate 17, as also shown in the drawings. The supporting plate 23 will thereby be guided properly in its vertical movement and assist in supporting the tractor.

By referring to Figure 4 of the drawings, it will be seen that the supporting brackets 18 are bifurcated between which the supporting wheels 20 are positioned. The structure serves to securely support the axles 19 for the wheels 20. It will be noted by referring to Figure 4 of the drawings that the wheels 20 preferably have peripheral channels which are of substantially V-shape construction in cross section, as shown at 29, so as to conform to the rails 1 which are preferably of inverted U-shape construction, as also shown clearly in Figure 4 of the drawings.

By referring to the foregoing paragraph taken in connection with the accompanying drawings, it will be seen that the forward jack structure may be adjusted upon the track rails 1 independently of the rear jack structure and each of the forward and rear

jack structures may be manipulated independently of each other to raise and properly support the sections of the tractor resting thereon, while the portions of the tractor are separated during the operation of removing or replacing the wheels or repairing any other portion of the tractor. It will be evident that any suitable means may be employed to prevent movement of the forward jack structure upon the track and the portion of the tractor resting thereon, when desired.

While the preferred embodiment of the invention has been shown and described, it will be understood that minor changes in the details of construction and arrangement of parts may be resorted to within the scope of what is claimed without departing from the spirit of the invention.

What is claimed is:

1. A jack of the character described comprising a supporting track, an immovable jack structure for supporting a portion of a tractor above said track, and a movable jack structure mounted on said track and adapted to operate independently of the first-mentioned jack structure to support a portion of the tractor above said track.

2. A jack of the character described comprising an immovable jack structure, a track, said immovable jack structure being mounted on said track and including a supporting base and a supporting plate, means for adjusting said supporting plate with respect to said supporting base, and a forward jack structure adjustable along the said track and adapted to be manipulated independently of the rear jack structure.

3. A jack of the character described comprising a track, a stationary jack structure secured upon said track, a movable jack structure mounted on said track and including a supporting base, supporting plates positioned above and adjustable with respect to said supporting base, said supporting plate carrying supporting members upon its upper face, and guide means for said supporting plate.

4. A jack of the character described comprising a pair of jack members including supporting bases and supporting plates, means for adjusting said supporting plates vertically with respect to said respective supporting bases, one of said jack members being movable upon a track and adjustable with respect to the remaining jack member, and guide means for the supporting plates of said jack members.

5. A jack of the character described comprising a track, a base member of a jack structure secured upon one end of the track, a supporting plate adjustably mounted on said base member, a second jack structure including a supporting base, a supporting plate adjustably mounted upon the sup-

porting base of the second jack structure, bracket members depending from the base of said second jack structure, and supporting wheels mounted in said bracket members and adapted for movement upon the rails of said track to adjust the second jack structure with respect to the first mentioned jack structure.

6. A doley comprising a pair of jack structures of which one jack structure is movable with relation to the other.

7. A doley comprising a base, a pair of jack structures carried by said base of which

one of said jack structures is movable on the base with relation to the other. 15

8. A doley comprising a pair of jack structures, and wheels supporting one jack structure to permit it to be moved with respect to the other.

In testimony whereof I affix my signature 20 in presence of two witnesses.

CHARLES E. KOSTER.
